UNITED STATES PATENT OFFICE.

ARTHUR D. PRATT, OF NEW YORK, N. Y., ASSIGNOR TO THE BABCOCK & WILCOX COMPANY, OF BAYONNE, NEW JERSEY, A CORPORATION OF NEW JERSEY.

STEAM-BOILER.

1,267,114.

Specification of Letters Patent. Patented May 21, 1918.

Application filed February 8, 1917. Serial No. 147,302.

To all whom it may concern:

Be it known that I, ARTHUR D. PRATT, a citizen of the United States, residing at New York city, borough of Manhattan, county of New York, and State of New York, have invented certain new and useful Improvements in Steam-Boilers, of which the following is a specification.

My invention relates to steam boilers and more particularly to those of the general Stirling type and will be understood by reference to the accompanying drawings in which Figure 1 is a vertical longitudinal section of one embodiment thereof, certain parts being broken away. Figs. 2, 3 and 4 are similar views showing modifications as will be described more fully hereinafter. Similar reference numerals indicate similar parts in the several views.

Referring to Fig. 1, the boiler shown comprises transverse upper steam and water drums 1, 2 and 3 and a mud drum 4, the upper drums being connected to the mud drum by banks of tubes 5, 6 and 7. I may use a single mud drum 4, as shown, or a series of connected mud drums, and I intend to cover both structures by the words "lower chamber" in the claims. The three upper steam and water drums must, however, be connected to this lower chamber whether in the form of one drum or several connected drums. The steam space of the center drum 2 is interconnected with the front and rear drums by curved steam circulating tubes 8 and 9. The water spaces of the front and middle drums are connected by water circulating tubes 10, the upper row of which tubes support tiling 11. In the forms shown there are no water circulators between the middle and rear steam and water drums. A baffle 12 is supported upon the first row of tubes of the front bank and extends upwardly from a point back of the bridge wall 13 to the upper end of the bank. A suitable seal 14 extending from tube clamps at the lower ends of the front row of tubes of the bank 5 to the bridge wall 13 prevents short circuiting of the gases, as more particularly described in the application of D. S. Jacobus, Serial No. 55,771, filed October 14, 1915.

The middle bank of tubes 6 is provided with two baffles, one of which 15 is supported upon the first row of tubes and extends downwardly from the middle steam and

water drum, and the other, 16, is supported upon the rear row of tubes and extends upwardly from the mud drum. A cross baffle or shelf 17 extends from the baffle 16 to substantially the first row of tubes of the rear bank. In the latter bank is a baffle 18 supported upon tubes at the rear of the bank and extending downwardly from the rear steam and water drum. The gases flow upwardly in front of the front bank of tubes, across the latter bank at the upper part thereof into the secondary combustion chamber 19, downwardly over the tubes of the front bank at the rear of baffle 12, thence upwardly over the tubes of the middle bank, downwardly over the tubes of the rear bank and then upwardly in the final pass back of the rear bank to the outlet 20.

As shown in Fig. 1, the furnace gases pass over a comparatively small portion of the heating surface before entering the chamber 19 permitting thereby an effective secondary combustion in this chamber. If desired, a superheater may be placed in the chamber 19. In the form shown such superheater comprises the cross boxes 21 and 22 to which the upwardly projecting U-tubes 23 are connected. The boxes are supported in saddles resting upon the cross beam 24 forming part of the structural work of the setting. The outlet box 22 is at a higher level than the inlet box 21 and is placed in proximity to the rear row of tubes of the front bank but far enough away therefrom to allow for the easy expansion of the superheater tubes into the box 22, and to allow a boiler tube to be passed between the rear of the front bank of tubes and said box when replacing a boiler tube. The outlet box 21 is in close proximity to the middle bank of tubes, such spacing apart of the superheater boxes lessening the overturning moment of the superheater tubes and providing a superheater which does not require supports for the tubes other than the cross boxes or headers.

In the standard Stirling boiler the front and rear steam and water drums are on substantially the same level and below the middle drum, and the main steam outlet is placed on top of the middle drum. According to the arrangement shown in Fig. 1 the rear steam and water drum is set higher than the usual practice, and on substantially

the same level as the middle drum, and the main steam outlet 25 is placed on top of the rear drum.

In the steam space of the rear drum is a dry pipe 26, the main steam outlet connecting therewith and delivering the steam to the inlet box 21 of the superheater. A feed pipe 27 enters the top of the rear drum 3 and discharges into a trough from which the water is distributed to the drum. A plate 28 is placed in the rear drum between the steam inlets 9 and the dry pipe 26 to deflect any water in the steam toward the bottom of the drum. With the steam spaces interconnected as shown, the water level in the rear drum will at all times be well below the level of the dry pipe. Experiments have demonstrated that the water level in the rear drum of a standard Stirling boiler with the steam space of the middle drum interconnected to both the front and rear drums by steam circulating tubes, is higher under certain conditions of operation with water containing a material amount of elements in solution than it is with a purer water. It is, therefore, not only advantageous, but highly important, to raise the rear drum to the level of the middle drum when the feed water is of such nature that it will lead to relatively high concentrations in the water contained in the boiler.

The form shown in Fig. 1 is especially adapted to waters containing impurities which tend to produce foaming and priming, and drier steam can be secured and supplied to a superheater than with a standard arrangement in which the steam is taken from the middle drum. By raising the rear drum above the standard position, the dry pipe 26 is correspondingly raised above the water level in the rear drum and this eliminates any trouble which might occur when there is high water in the boiler, with the rear drum at a lower level because of water being carried along with the steam into the dry pipe. Even should there be a high degree of concentration of foreign elements in the water in the boiler, tending to produce priming, the steam supplied to the superheater will be comparatively dry and by reason of this a superheater of a given size will give a greater degree of superheat under such conditions, than in the standard construction in which the steam is taken from the middle drum.

The drums are of the usual type, that is, made up of a shell sheet and a tube sheet, butt-jointed and secured with double longitudinal straps 29. In order to deflect the gases downward after they leave the upper part of the middle bank of tubes and to prevent direct impingement of the gases upon the rear steam and water drum, and to protect the butt straps of the middle and rear drums, I provide a special baffle

which extends from the middle drum below the rear butt strap thereon, to a point below the rear steam and water drum, substantially as shown. This baffle is shown as inclined downwardly from the middle steam and water drum and is supported upon the bent upper ends of a row of tubes 31 extending from the lower water chamber and passing in close proximity to the rear upper drum, and with their upper ends connected to the middle upper drum. Not only are the middle and rear drums protected in the manner stated but the special baffle 30 prevents the hot gases striking the upper portions of the tubes of the rear bank. When the boiler is run at high ratings the water level may fall below the top of the tubes, and by preventing the hot gas from striking the tops of the tubes the danger of overheating the tubes is eliminated.

In Fig. 2 I have shown my special protecting baffle 30 in a Stirling boiler having the standard baffling, but with the rear steam and water drum on substantially the same level as the middle steam and water drum, as in Fig. 1, and another type of superheater in the chamber between the front and middle banks. In this form a baffle 32 is supported upon the rear row of tubes of the front bank 5 and extends upwardly from the mud drum to the upper part of the bank. A baffle 33 is supported upon the rear row of tubes of the middle bank 6 and extends downwardly from the middle steam and water drum 2. Horizontal shelves 34 extend from the rear wall of the setting toward the rear bank. The gases flow upwardly along and among the tubes of the front bank, thence in a general downward direction over and among the tubes of the middle bank, thence upward over the tubes of the rear bank to the outlet 20. If desired, a superheater may be placed in the chamber between the front and middle banks of tubes. In the form shown in Fig. 2, the superheater comprises cross boxes 35 and 36 to which the upwardly projecting U-tubes 37 are connected. The tubes, in this form of superheater, extend substantially parallel with the tubes of the middle bank, their upper ends being in close proximity to the middle steam and water drum. Clamps secured to the front row of boiler tubes of the middle bank serve as supports for resisting the overturning moment of the superheater. The main steam outlet 25 is placed upon the rear steam and water drum and the steam is conducted therethrough to the superheater inlet box 36. An oil burning furnace is shown, the atomizers 39 being set in recesses in the bridge wall 40.

In Fig. 3 is shown a boiler having a baffle arrangement for the banks of tubes as in Fig. 1, but with the rear steam and water drum 3 set substantially the same

level as the front steam and water drum 1, and the main steam outlet 38 set upon the top of the middle steam and water drum as in standard practice. The dry pipe 26⁵ is, of course, transferred from the rear steam and water drum to the middle steam and water drum. Otherwise the parts are the same as in Fig. 1.

Fig. 4 shows a Stirling boiler standard 10 both as to the baffling for the banks of tubes, the setting of the steam and water drums and the location of the main steam outlet. Except for the difference in location of the rear steam and water drum 3^a, and the location of the main steam outlet 38, the parts and their arrangement are the same as in Fig. 2.

What I claim and desire to secure by Letters Patent of the United States is:—
20 1. A steam boiler of the class described comprising at least three upper transverse drums connected by banks of tubes to a lower water chamber, baffles for directing the gases over and among the tubes of said 25 banks, some of the tubes of the rear bank being connected to the middle upper drum, and a baffle supported upon the upper portions of said last-named tubes to protect the rear upper drum from excessive heating.
30 2. A steam boiler of the class described comprising at least three upper transverse drums connected by banks of tubes to a lower water chamber, baffles for directing the gases over and among the tubes of said 35 banks, the front row of tubes of the rear bank being connected to the middle upper drum, and a baffle supported upon the upper portions of said last-named tubes to protect the rear upper drum from excessive heating.
40 3. A steam boiler of the class described comprising at least three upper transverse drums connected by banks of tubes to a lower water chamber, baffles for directing

the gases over and among the tubes of said banks with an up-pass in the middle bank, 45 some of the tubes of the rear bank being connected to the middle upper drum, and a baffle supported upon the upper portions of said last-named tubes to protect the rear upper drum from excessive heating. 50

4. A steam boiler of the class described comprising at least three upper transverse drums connected by banks of tubes to a lower water chamber, the rear upper drum being at a higher level than the front upper 55 drum, a main steam offtake leading from said rear drum, baffles for directing the gases over and among the tubes of said banks, some of the tubes of the rear bank being connected to the middle upper drum, 60 and a special baffle supported upon the upper ends of said last-named tubes for protecting the middle and rear upper drums from excessive heating.

5. A steam boiler of the class described 65 comprising at least three upper transverse drums connected by banks of tubes to a lower water chamber, baffles for directing the gases over and among the tubes of said banks, steam circulators connecting the upper drums, water circulators between the front and middle upper drums, a feed water inlet leading into the rear upper drum, the front row of tubes of the rear bank being connected to the middle upper drum, and a 70 baffle supported upon the upper portions of said last-named tubes to protect the rear upper drum from excessive heating. 75

In testimony whereof I have hereunto signed my name in the presence of two subscribing witnesses.
